MOUNTING OF IMPRESSION PLATES ON PLATENS

John Irving Nasmith and Flavius Kingsford Daniels, London, England, assignors to Vickers-Armstrongs Limited, London, England, a British company

Application January 12, 1949, Serial No. 70,444
In Great Britain January 22, 1948

7 Claims. (Cl. 101—306)

1

The invention relates to the mounting of impression plates on platens, and it concerned more particularly with presses of the type wherein an impression is taken on an impression plate superimposed on and secured to the face of the platen, the work to be impressed being placed on the surface of such impression plate.

Machines of the type specified include printing, creasing or cutting presses with rotating platen.

In presses of the type specified, in order to obtain an even impression over the whole area of contact and the required flexibility to attain this, it is the practice to insert packing between the face of the platen and the lower surface of the impression plate, and local adjustment at any part of the surface may be necessary. A number of such adjustments may have to be made and the impression plate may have to be manipulated for this purpose a number of times before a satisfactory impression is obtained. It is therefore desirable to have ready means of access to any part of the impression area without completely removing the plate, but nevertheless allowing a sufficient amount of movement to leave plenty of manipulating space and a clear field of vision over this area. Further it is desirable that all parts should be equally accessible and visible.

A purpose of the invention is to provide improved means of mounting the impression plate to enable the initial adjustments required to be made readily and expeditiously.

According to one feature of the invention the impression plate is mounted for bodily movement, with respect to the platen, in a guided path between the position of rest and another stable position. This motion is preferably a parallel translatory motion with respect to the platen and to the position of rest of the impression plate. Further, the relative motion should be comparatively large and, to avoid accidents through inattention, it is desirable to connect the means for imparting the relative motion to the plate with safety means for preventing operation of the machine unless the plate is in the working position to receive impressions i. e. in the position of rest with respect to the platen.

According to a further feature of the invention the means for mounting and shifting the plate are self-locking both in the working position i. e. the position of rest of the plate and in the advanced position. A further feature of the invention is that the impression plate is readily detachable from the mounting mechanism. This feature is preferably realised by a

2

linkage for advancing the plate whilst the latter is guided in the desired relationship to the platen, the linkage being such as to follow the plate to be removed only when the latter is in the advanced position. The mounting does not however necessarily involve direct fastening means between the plate and the platen face and is always available for immediate manipulation. A form of mounting fulfilling these requirements 10 is one in which a linkage has points of support with the impression plate which whilst serving to impart the necessary motion to the plate are also arranged to have a limited degree of movement transversely with respect to the direction 15 of motion of the plate, which transverse movement may be employed for locking the plate in the advanced position.

An example of a preferred mounting according 20 to the invention will now be described in more detail with reference to the accompanying drawings, in which:

Figure 1 is a side elevation of the platen and impression plate of a cutting and creasing press with rotating platen, the impression plate being 25 shown in the working position in which it rests on the face of the platen.

Figure 2 is a similar view to that of Figure 1 but showing the impression plate raised from the platen.

Figure 3 is a front elevation in which the essential parts of the mechanism are shown in the position corresponding to that of Figure 1.

In these drawings some of the contiguous parts of the machine and the frame thereof are diagrammatically indicated in so far as they make clear the construction now to be described but these parts are not allotted reference numerals or specifically referred to in the description which follows.

The impression plate 1 has secured to it at 40 either side a supporting flange 2 such that when the impression plate is applied to the platen 3 the supporting flanges nest along the side edges of the platen and extend for substantially the full length of the said edges. The supporting flanges 2 each have a central open-ended slot 4 co-operating 45 with a guide pin 5 secured in the platen side, these slots being in a direction at right-angles to the face of the impression plate. At each end of each of the supporting flanges are provided inwardly open slots 6 extending in a direction parallel with the face of the impression plate. These slots co-operate with pins 7 in the lifting and positioning mechanism, and are such that 50 55 when the plate has been fully lifted by the said

mechanism, the plate and its supporting flanges may be bodily lifted off the machine and replaced by another similar unit when desired.

The lifting mechanism, which is duplicated at each side of the platen, comprises a pair of pivots 8 and 9 fixed to the platen casting and symmetrically disposed with respect to the centre line of the impression plate, on which are pivoted a pair of equal two-armed levers 10 and 11, the inner opposed arms of which are operatively interconnected by a pin 12 and slot 13 at the center line referred to and the outer arms of which support the impression plate by means of the pins 7 and slots 6 above referred to.

One arm of each of the functionally equal two-armed levers 10 at each side of the platen may be extended towards the front of the machine for the purpose of mounting a connecting and operating bar 14 and a spring catch or catches 15 mounted on the said extended arms. The catches 15 engage with a locating sector 16 fixed on the platen casting such that the impression plate may be locked in either of the extreme positions, that is in the advanced position (Fig. 2) or in the working position resting against the platen face (Fig. 1). The operating bar and locking means are conveniently so arranged that the impression plate may be unlocked and shifted from one position to the other in the same movement. When fully raised the impression plate is free to be removed from the lifting mechanism, the pins 7 on the levers having been shifted to the open ends of the slots 6 during the lifting operation. As will be seen from the figures, the symmetrical arrangement of levers 10 and 11 ensures parallelism of the plate, but the central slot 4 and pin 5 ensure that the motion of the plate is normal to the face of the platen. The impression plate may therefore be advanced from the platen with a parallel translatory motion which is ample for providing accessibility to all parts of the under face.

To prevent the machine being accidentally or inadvertently operated whilst the impression plate is in the raised position, which would result in serious damage, the plate lifting levers are provided with safety mechanism interconnected with the starting pedal of the machine. Such interconnection may be effected as shown by a stop lever 18 pivoted on the machine frame at 17, one end of which lever co-operates with a lever 19 connected with the machine starting pedal and the other end of which is connected to the plate lifting means by a radial linkage 20. When the impression plate is in the normal working position, starting and operation of the machine can take place, but as soon as the plate is raised the stop lever locks the starting means and the machine cannot then be started until the plate has been restored to the working position.

We claim:

1. In combination with a platen, an impression plate normally secured in a stable position to the face of the platen, mechanism for supporting and shifting the impression plate from said normal stable position to a second stable position spaced from, and parallel to, the platen and affording access to the surface of the platen, means for actuating said mechanism to shift the impression plate from one stable position to another, means for operating the platen, a linkage mechanism operatively connected to said supporting and shifting mechanism of the impression plate, and means for causing said linkage mechanism to

engage said operating means to prevent operation of the platen when the impression plate is in said second stable position spaced from the platen.

5. In combination with a platen, an impression plate normally secured in a stable position to the face of the platen, mechanism for supporting and shifting the impression plate from said normal stable position to a second stable position spaced from, and parallel to, the platen and affording access to the surface of the platen, said mechanism comprising levers pivotally connected to the platen at points intermediate their ends, a support at one end of each of said levers for supporting the impression plate, means for actuating said levers to shift the impression plate from one stable position to the other, means for operating the platen, a lever device for controlling said operating means, a link pivotally connected to at least one of said impression plates supporting levers, locking means engageable with said lever device to prevent operation of the platen, means operatively connecting said link to said locking means, and means for causing said locking means to engage with said lever device to prevent operation of the platen when the impression plate is in said second position spaced from the platen, and for releasing said locking means when said impression plate is moved into its normal position on the face of the platen.

3. In combination with a platen, an impression plate normally secured in a stable position to the face of the platen, mechanism for supporting and shifting the impression plate from said normal stable position to a second stable position spaced from, and parallel to, the platen and affording access to the surface of the platen, said mechanism comprising levers pivotally connected to the platen at points intermediate their ends, supporting pins at the ends of said levers, bearing surfaces on said impression plate engageable by said supporting pins, said bearing surfaces extending parallel to the face of the impression plate and serving as guides for said pins, slots adjacent said bearing surfaces and engageable by said pins to lock the impression plate in said normal stable position, means for actuating said shifting mechanism to move the impression plate to its second stable position spaced from the platen, and to disengage said pins from the slots so that the plate, when in its said second stable position, can be lifted from said pins, means for operating the platen, means including a lever for controlling said operating means, link mechanism operatively connected to said supporting and shifting mechanism of the impression plate, and means for causing said link mechanism to engage with said lever to prevent operation of the platen when the impression plate is in said second stable position.

4. A press comprising, in combination, a platen, an impression plate normally secured in a stable position to the face of the platen, mechanism for supporting and shafting the impression plate from said normal stable position to a second stable position spaced from, and parallel to, the platen and affording access to the surface of the platen, said mechanism comprising a pair of levers pivotally connected to the platen on either side thereof, pins at the ends of said levers for supporting the impression plate, side flanges on the impression plate, bearing surfaces at each end of said side flanges and engageable by said supporting pins, said surfaces extending in a direction parallel with the face of the impression

plate to ensure parallelism of said plate, recesses at the outer ends of said bearing surfaces for engagement by said pins to lock the pins to said impression plate when the latter is in its normal stable position, an extension on at least one of the levers of said shifting mechanism, a spring catch mounted on said extension, a member mounted on the platen and engageable by said spring catch to maintain the impression plate in either one of said stable positions, means for actuating the shifting mechanism to move the impression plate into, and away from, its said normal stable position, means for operating the press, means including a lever device for controlling said operating means, a link pivotally connected to at least one of the levers of said shifting mechanism, locking means engageable with said lever device to prevent operation of the press, means operatively connecting said link to said locking means, and means for causing said locking means to engage with said lever device to prevent actuation of the platen when the impression plate is in said second stable position, and for releasing said locking means when said impression plate is into its normal stable position on the face of the platen.

5. In a press, the combination of a platen, an impression plate normally secured in a stable position to the face of the platen, mechanism for supporting and shifting the impression plate from said normal stable position to a second stable position spaced from, and parallel to, the platen and affording access to the surface of the platen, said mechanism comprising levers pivotally connected to the platen at points intermediate their ends, pins at the supporting ends of said levers for supporting said plate, flanges on opposite sides of said impression plate, bearing surfaces formed in said flanges and engageable by said supporting pins, means for actuating said shifting mechanism to move the impression plate from one stable position to the other, means for operating the press, a pedal for controlling said operating means, a stop lever connected with said pedal, an arm pivotally mounted on the press frame and engageable with said stop lever to prevent said pedal from being operated to start the press, a link pivotally connected at one end to a lever of the impression plate shifting mechanism, the opposite end of said link being pivotally connected to said arm so that, when the impression plate is shifted into said second stable position, said link rocks the pivoted arm into engagement with the stop lever to prevent said pedal from being actuated to start the press.

6. In a press, the combination of a platen, an impression plate normally secured in a stable position to the face of the platen, mechanism for supporting and shifting the impression plate from said normal stable position to a second stable position spaced from, and parallel to, the platen and affording access to the surface of the platen, said mechanism comprising a pair of levers arranged on each side of the platen, the levers being pivotally connected to the platen at points intermediate their ends, means associated with said levers for retaining the impression plate in either one of its stable positions, means for actuating said shifting mechanism to move

the impression plate from one stable position to the other, means for operating the press, a pedal for stopping and starting said operating means, an arm pivotally mounted on the press frame and engageable with a part of said pedal to hold the latter in the stop position, a link, one end of which is pivotally connected to a lever of the impression plate shifting mechanism, and the other end of which is pivotally connected to said arm, said link rocking said arm, when the impression plate is shifted into said second stable position, to cause said arm to engage said pedal and lock the latter in its stop position.

7. A press comprising in combination, a platen, an impression plate normally secured in a stable position to the face of the platen, mechanism for supporting and shifting the impression plate from said normal stable position to a second stable position spaced from and parallel to, the platen and affording access to the surface of the platen, said mechanism comprising levers pivoted in the platen symmetrically of a principal axis of the impression plate, pins at the supporting ends of the levers, side flanges on said plate arranged to nest along the edges of the platen, bearing surfaces for said pins at the ends of the side flanges, said surfaces being parallel with the face of the impression plate, recesses at the outer ends of said bearing surfaces, said recesses being engaged by said pins when the impression plate is moved into its normal stable position, a central open-ended slot on each side flange normal to the face of said plate, a guide pin mounted on each side of the platen and engageable with said central slot to ensure parallel motion of the impression plate normal to the surface of the platen, a spring catch device for releasably holding the impression plate in either one of said stable positions, means for actuating the shifting mechanism to move the impression plate from one stable position to the other, means for operating the press, a pedal for controlling said operating means, a stop lever connected with said pedal, an arm pivotally mounted on the press frame and engageable with said stop lever to prevent said pedal from being operated to start the press, a link, one end of which is pivotally connected to a lever of the impression plate shifting mechanism, and the other end of which link is pivotally connected to said arm so that, when the impression plate is shifted into the second stable position said link rocks the pivoted arm into engagement with the stop lever to prevent said pedal from being actuated to operate the press.

JOHN IRVING NASMITH.
